(57) **CLAIM**

The ornamental design for a floating platform, as shown and described.

DESCRIPTION

FIG. 1 is a top perspective view of a platform for yachts; FIG. 2 is a bottom perspective view thereof;

FIG. 3 is a left side view thereof;

FIG. 4 is a right side view thereof;

FIG. 5 is a front view thereof;

FIG. 6 is a rear view thereof;

FIG. 7 is top view thereof; and,

FIG. 8 is a bottom view thereof.

The shading lines shown in the drawing represent the three-dimensional contour of the claimed design, and are not intended to indicate surface decoration.

1 Claim, 8 Drawing Sheets
